JEWELRY BOX

William H. Meeker, 128 Russell Ave., Rochester, N.Y.

Filed May 1, 1964, Ser. No. 79,762

Term of patent 14 years

(Cl. D58—12.7)

FIG. 1

FIG. 2

FIG. 3

FIG. 4

FIG. 5

FIG. 6

FIG. 1 is a perspective view from above of a jewelry box embodying my new design in closed position;

FIG. 2 is a perspective view from below;

FIG. 3 is a perspective view thereof from above with the covers in open position;

FIG. 4 is similar to FIG. 3 with the cover and top compartments moved away to expose the middle compartments;

FIG. 5 is similar to FIG. 3, but with the top and middle compartments moved away to expose the bottom compartments; and

FIG. 6 is similar to FIG. 5 with the cover portion moved away to expose the uppermost compartments.

The dominant features of my design reside in the portions shown in full lines.

I claim:

The ornamental design for a jewelry box, substantially as shown and described.
